(57) **CLAIM**

The ornamental design for a fender vent for a vehicle, as shown and described.

DESCRIPTION

FIG. 1 is a front right elevated perspective view of a fender vent for a vehicle according to the present invention.

FIG. 2 is a front right perspective view of the fender vent shown in FIG. 1.

FIG. 3 is a rear left elevated perspective view thereof.

FIG. 4 is a rear left perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof.

FIG. 10 is a bottom view thereof; and,

FIG. 11 is another front view thereof, but with the fender vent of FIGS. 1-10 shown mounted on an unclaimed vehicle that is shown in broken lines, and which forms no part of the claimed design. Rather, the broken lines that surround the fender vent serve as an unclaimed boundary.
